UNITED STATES PATENT OFFICE.

CHARLES WALTER MACWILLIAMS, OF GENEVA, NEBRASKA.

OVERSHOE.

1,204,293.

Specification of Letters Patent. Patented Nov. 7, 1916.

Application filed March 28, 1916. Serial No. 87,261.

To all whom it may concern:

Be it known that I, CHARLES WALTER MACWILLIAMS, a subject of the King of England, and a resident of Geneva, in the county of Fillmore and State of Nebraska, have invented a certain new and useful Improvement in Overshoes, of which the following is a specification.

My present invention relates generally to overshoes, and more particularly to thin flexible overshoes of the glove fitting type, my object being to provide such an overshoe with a toe-engaging protuberance or projection located so that the shoe of the nature described may be readily removed without applying the hands to this purpose. Ordinarily as well known, toe-engaging protuberances are provided at the rear end or heel portion of an overshoe, but such protuberances are inoperative, located at the point described, for withdrawing overshoes of the thin flexible nature to which my present improvements relate.

The invention consists therefore in the protuberance arranged in the particular position and manner to be hereinafter described with reference to the accompanying drawing, forming a part of this specification, and wherein—

Figure 1 is a perspective view illustrating the protuberance in the nature of a knob-like projection located in accordance with my invention. Fig. 2 is a partial vertical cross section taken substantially on line 2—2 of Fig. 1. Fig. 3 is a view similar to Fig. 1 illustrating the protuberance in the nature of a lip extension of the sole of the overshoe, and Fig. 4 is a view similar to Fig. 2 though taken substantially on the line 4—4 of Fig. 3.

Referring now to these figures, my invention proposes the location of a protuberance in connection with thin flexible overshoes, extending laterally from the inner side portion of the shoe adjacent the

lower instep portion thereof, as in all of the figures.

In the form of the invention shown in Figs. 1 and 2, this protuberance takes the nature of a knoblike projection 10 preferably forming part of a protecting cap or disk 11 secured to the lower instep portion of the overshoe 12 at the inner side thereof, all as clearly seen by a comparison of the figures mentioned.

In accordance with the form shown in Figs. 3 and 4, the protuberance takes the nature of an extension lip 13 preferably integral with, and forming a part of, the sole portion of the overshoe 14 at the inner side of the instep thereof.

A protuberance constructed either as shown in Figs. 1 and 2, or as shown in Figs. 3 and 4, is not only particularly effective in removing thin flexible overshoes of the glove fitting type, without applying the hand to this purpose, but is also, as located, particularly advantageous over the ordinary projection or protuberance at the rear or heel portion of an overshoe, inasmuch as by locating the protuberance at the instep, an effective guide is constituted for the toe of the other shoe, preventing slipping and displacement from the projection as the overshoe is being withdrawn or removed.

I claim:

1. A flexible overshoe having a protuberance extending laterally from its inner side adjacent the lower instep portion thereof, for the purpose described.
2. A flexible overshoe having its sole provided with an extending lip projecting laterally thereof at the inside of the overshoe adjacent the instep portion thereof, for the purpose described.

CHARLES WALTER MACWILLIAMS.
